UNITED STATES PATENT OFFICE.

CHARLES NELSON, OF BROOKLYN, NEW YORK.

PACKAGE.

SPECIFICATION forming part of Letters Patent No. 514,159, dated February 6, 1894.

Application filed March 23, 1893. Serial No. 467,366. (No model.)

To all whom it may concern:

Be it known that I, CHARLES NELSON, a citizen of the United States, residing at Brooklyn, in the county of Kings and State of New York, have invented new and useful Improvements 5 in Packages, of which the following is a specification.

This invention relates to a torpedo shaped package composed of an interior layer of paper or other flexible material a covering pasted to the interior layer and a wrapper stretched over the package and provided with a pointed tail as set forth in the following specification and claim and illustrated in 15 the annexed drawing in which is shown an elevation of the package partly in section.

In the drawing the letter A indicates an interior layer of paper or other flexible material to which is pasted a covering or layer B 20 of strong paper or such substance as linen. A wrapper C is stretched over the package or covering B and provided with or twisted into a pointed tail D. By providing the wrappers at the tail with adhesive or paste the tail D 25 when twisted into shape will not come undone. A piece of card board or stiffening material E placed in the bottom of layer A and provided with a hole or perforation F will enable the package to be evenly or properly cut or 30 broken at said perforation F to remove the contents of the package.

The contents are placed into the package before the tail D is twisted shut.

The package is ornamental and suggestive for such articles for example as torpedoes 35 which are shown at G as constituting the contents of the box.

The package is easily and cheaply formed and can be readily cut or opened at the perforation F of the diaphragm or stiffening 40 piece E the rim of said opening F forming a guide by following which irregular or excessive tearing or rupturing of the package in opening is prevented.

What I claim as new, and desire to secure 45 by Letters Patent, is—

A torpedo shaped package composed of an interior layer of paper or other flexible material a covering pasted to the interior layer and a wrapper stretched over the package 50 and provided with a pointed tail and a perforated stiffening piece placed in the bottom of said interior layer substantially as described.

In testimony whereof I have hereunto set 55 my hand in the presence of two subscribing witnesses.

CHARLES NELSON.
